UNITED STATES PATENT OFFICE.

CHARLES M. STROUD, OF MINNEAPOLIS, MINNESOTA, ASSIGNOR OF ONE-HALF TO
LELIE H. FAWKES, OF MINNEAPOLIS, MINNESOTA.

OIL BURNER.

Application filed December 19, 1924. Serial No. 756,908.

This invention relates to improvements in oil burners particularly adapted for use in connection with steam or hot water boilers or hot air furnaces of the coal-burning type, 5 such as are commonly employed for heating various types of buildings, and, by the use of which such a furnace may readily and quickly be converted into a liquid fuel burning furnace with a minimum amount of labor.

10 The particular object of this invention is to provide an oil burner which is an improvement on the form of burner featured in my prior pending application, filed September 4, 1924, Serial No. 735,867.

15 A further object of the invention is to provide an oil burner comprising a retort into which the liquid fuel oil or distillate is delivered in substantially a raw state, and wherein it is partially vaporized, after which 20 the thus partially vaporized fuel passes through a series of vaporizing tubes wherein it will be thoroughly and completely vaporized before being discharged into the path of the inrushing air currents for admixture 25 therewith, thereby providing a highly combustible mixture which may readily be ignited for subsequent combustion.

30 A further object is to provide an oil burner having a simple means whereby it may readily and conveniently be leveled upon installation, should the foundation upon which it is mounted be uneven.

35 A further object is to provide an oil burner comprising the utmost in simplicity and efficiency and one which will be positive and fool-proof in performance when operated in conjunction with the usual well-known control apparatus.

40 Other objects of the invention will appear from the following description and the accompanying drawings and will be pointed out in the annexed claims.

45 In the drawings, there has been disclosed a structure designed to carry out the various objects of the invention, but it is to be understood that the invention is not confined to the exact features shown, as various changes may be made within the scope of the claims which follow.

50 In the accompanying drawings forming a part of this specification,

Figure 1 is a vertical sectional view of the improved oil burner;

Figure 2 is a horizontal sectional view on the line 2—2 of Figure 1; 55

Figure 3 is a similar view on the line 3—3 of Figure 1.

The novel oil burner featured in this invention comprises a metallic base 4, preferably circular in form, having a cover 5 mounted thereon. A shallow pan 6 is centrally mounted in the base 4 and is preferably supported therein by means of integral arms 7 as particularly shown in Figure 2. By this arrangement of the pan 6 within the base, it will be noted that openings 8 will be provided between the radial arms 7, and through these openings air is supplied to the burner as will subsequently be described. A central opening 9 is provided in the cover 5 and this opening is encircled by a depending flange 11 formed on the cover. The lower edge of the flange 11 preferably extends slightly below the upper edge of the flange 12 of the pan 6 so that when the air passes 75 upwardly through the openings 8, it must follow a tortuous path, as indicated by the arrows in Figure 1.

The shallow pan 6 of the base 4 is preferably provided with a central boss 13 in which the lower end of an upwardly extending pipe section 14 is secured. A nipple 15 is secured to the under side of the pan 6 in alignment with the pipe 14 and is connected to an oil feed pipe 16 by means of an elbow 85

17. A priming pan 18, of relatively smaller diameter than the diameter of the central opening 9 of the cover 5, is loosely mounted on the pipe section 14 and is supported upon the boss 13 as shown. Thus, an annular 90 opening will be provided between the upturned outer flange of the priming pan and the depending flange 11 of the cover 5.

The means provided for vaporizing the fuel in this novel burner preferably consists in the provision of a retort 19 mounted on the upper end of the pipe section 14. A cover 21 is mounted on the retort to provide a closure for the top thereof. A series of vaporizing tubes 22 are secured to the bottom of the retort 19 and extend downwardly therefrom substantially in parallel relation to the pipe section 14, to a point near the top of the cover 5. A skirt-like member or hood 23 is mounted on the retort 19 and is preferably supported by means of a pe- 100 105

peripheral flange 24 integrally formed thereon as shown in Figure 1. This hood surrounds the vaporizing tubes 22 and provides a heating chamber therefor in which the tubes 22 may be heated to a very high temperature and a thorough and complete vaporization of the fuel effected as it passes downwardly therethrough. It will also be noted that the retort is provided with a central boss 25 which preferably extends a distance above the bottom thereof so that as the fuel oil is delivered to the retort, it will overflow the boss and will be equally distributed to the vaporizing tubes 22. An air circulating tube or pipe 20 is preferably provided to establish communication between the retort 19 and the interior of the burner base 4 as shown in Figure 1. This pipe has its upper end suitably secured to the cover 21 of the 10 retort and its lower end to the cover 5 of the burner base. By means of this pipe heated air will be supplied to the retort which functions to prevent carbonization of the fuel oil therein and to keep the retort 20 clean.

A means is also provided whereby the burner, when installed, may readily and conveniently be leveled should the foundation upon which it is mounted be uneven. 30 Such means preferably consists in mounting the base 4 in an intermediate member 26 which is adjustably mounted in the upper portion of an air-trunk 27 through which air is supplied to the burner. The leveling member 26 is preferably provided with an inwardly projecting bead 28 which forms a seat for the base 4 when mounted therein. The lower portion of the member 26 is preferably reduced in diameter so as to provide 35 the reduced portion 29 which is adapted to be seated within an opening 31 provided in the upper portion of the air-trunk 27. The wall of the reduced portion 29 is preferably frusto-conical in shape so that when seated 40 in the opening 31 it will be wedged against the upper edge thereof as shown in Figure 1, thereby providing substantially an air-tight connection and also allowing the burner proper, and the lifting member to 45 be tilted with reference to the air-trunk 27. As a result of the wall of the reduced end portion 29 being inclined, as shown, it will maintain its adjusted position by frictional contact with the wall of the opening 31, 50 thereby providing a very simple and inexpensive means for adjusting or leveling the oil burner upon installation. This is an important feature as in many installations, it is necessary to provide special foundations to support the burner in order that 55 it may be substantially level when installed.

The air-trunk 27 is preferably mounted upon a base plate 32 of a suitable material such as cast iron. An overflow pipe 33 60 is also preferably connected to the pan 6

and outwardly leads therefrom through the vertical wall of the leveling member 26, as shown in Figure 2.

In the operation of this novel oil burner, liquid fuel is supplied to the feed pipe 16 from a suitable source, not shown, and flows upwardly through the nipple 15, pipe section 14 and into the retort chamber 19 mounted at the upper end thereof. As the oil enters the retort chamber 19 it will overflow the top of the boss 25 and will be distributed to the vaporizing tubes 22 through which it will flow downwardly into the priming pan 18. It may then be ignited by any suitable means such as a pilot light, 70 after which the pipe 14 and also the vaporizing tubes will become heated from the burning oil in the priming pan 18. As soon as the pipe 14 and the tubes 22 become sufficiently heated to cause the oil to vaporize, 75 it will be mixed with the inrushing air entering through the annular opening between the outer edge of the priming pan 18 and the depending flange 11, thereby providing a highly combustible mixture which will immediately be ignited. As soon as the burner has been well started, the retort chamber 19, and also the vaporizing tubes 22 will become heated to a very high degree of temperature, thereby causing the fuel oil to be 80 thoroughly vaporized before it is discharged from the lower ends of the vaporizing tubes into the path of the inrushing air. The hood 23 functions to provide a heating chamber for the vaporizing tubes 22 and the lower 85 edge thereof also functions to deflect the mixture of vaporized fuel and air outwardly against the walls of the furnace.

Air is preferably supplied to the burner through the trunk 27 which may be connected to a suitable source of supply, or if desired, a small fan may be interposed in the outer end of the trunk to provide the desired volume of air therethrough. By means of the upturned outer flange 12 of the shallow 90 pan 6 and also as a result of the depending flange 11 of the cover 5, the air will follow a tortuous path as indicated by the arrows. Through the annular opening around the priming pan 18, the air will be upwardly directed towards the hood 23 thereby becoming heated and thoroughly mixed with the vaporized fuel after which it is blown outwardly through the gap between the lower edge of the hood 23 and the cover 5 against the walls 95 of the furnace. In case of ignition failure in starting the burner, the liquid fuel will be discharged into the priming pan 18 and will overflow the edge thereof and be discharged into the relatively larger pan 6, positioned 100 therebeneath. From this pan, the overflow oil will flow through the pipe 33 to an automatic shut-off means whereby the supply of fuel to the feed pipe 16 will automatically 105 be cut off. The mechanism provided for thus 110

automatically cutting off the fuel supply in case of ignition failure is standard and well known to those familiar with the art, and therefore need not be shown in the drawings.

5 I claim as my invention:

1. A liquid fuel burner, comprising a base having a priming pan and an air intake opening in the plane of and circumscribing the pan, a retort supported above said base 10 and having a liquid fuel feed pipe, and flues depending from said retort to a point near said base and over said pan and adapted to deliver the vaporized fuel directly thereupon to mingle with the air from said circumscribing intake opening, and means for deflecting the burner flame outwardly from said base.

2. A liquid fuel burner, comprising a base having a priming pan and an air intake 20 opening circumscribing the pan, a retort supported above said base and having a liquid fuel feed, a flue for the vaporized fuel depending from said retort overhanging the pan to deliver the vapor to mingle with the 25 air from said intake and a hood encircling said flue and cooperating with said base to form a mixing chamber and adapted to deflect the flame outwardly from said base.

3. A liquid fuel burner, comprising a base, 30 having a priming pan and an air intake opening surrounding the pan, a liquid fuel feed pipe projecting upwardly from said base, a retort mounted on said feed pipe and having a depending flue overhanging the 35 pan, a hood encircling said flue for deflecting the burner flame outwardly, said feed pipe becoming heated by the flame of said priming pan for the initial vaporization of the fuel and said flue discharging the 40 vaporized fuel at a point adjacent said air intake opening to mingle with the air therefrom.

4. A liquid fuel burner, comprising a base having a central priming pan and an air 45 intake opening bordering and surrounding the pan at the level thereof, a retort supported above said base and having a liquid fuel feed, a flue depending from said retort and adapted to deliver the vapor at a point over the 50 pan to mingle with the air from said intake opening, and means for delivering air to said retort to mingle with the fuel therein.

5. A liquid fuel burner comprising a base 55 having a central priming pan, and an air intake opening bordering and surrounding the pan, a retort supported above said base and having a liquid fuel feed pipe leading thereto, a flue depending from said retort and adapted to deliver the vapor to mingle 60 with the air from said intake opening, a hood enclosing the flue, overhanging and extending beyond the air intake opening for deflecting the burner flame outwardly on said base to a point beyond said air intake, and 65 means for delivering air to said retort, said

means comprising a pipe communicating with the intake opening of said base and leading therefrom to the upper portion of said retort.

6. A liquid fuel burner, comprising a base, 70 having a priming pan and an air intake opening, a liquid fuel feed pipe projecting upwardly from said base, a retort mounted on said feed pipe, a series of flues depending from said retort around said feed pipe and terminating near said priming pan and said intake opening, a hood supported by said retort and encircling said flues and feed pipe, and depending to a point near said base and above and on the outer side of said air intake opening and cooperating therewith to form a mixing chamber.

7. A liquid fuel burner, comprising a base, 75 having a centrally arranged priming pan and tortuous air intake openings grouped around said burner, a liquid fuel feed pipe projecting upwardly through said base and pan, a retort supported on said feed pipe, flues depending from said retort to a point near said pan and intake opening, said feed 80 pipe becoming heated upon the ignition of the fuel in said priming pan for the initial vaporization of the fuel, and a flaring hood depending around said flues and cooperating with said base to form a mixing chamber 85 and deflector for the burner flame.

8. A liquid fuel burner, comprising a base, 90 having a central priming pan and air intake opening bordering and surrounding the pan, a liquid fuel feed pipe mounted on said base, 100 a retort supported by said feed pipe, flues depending from said retort to deliver the vapor therefrom adjacent to and inwardly from said intake opening and upon the pan.

9. A liquid fuel burner comprising a base 105 having openings for receiving air through its bottom, a central priming pan above the base, a feed pipe extending upwardly through base and pan and a removable cover for said base having a central opening therein circumscribing and spaced from the pan forming therewith an annular air intake opening, said cover forming with the base an air channel communicating with said annular intake opening, a retort upon said feed 115 pipe and flues depending from said retort overlying and spaced upwardly from said pan.

10. A liquid fuel burner, comprising a 120 base having a priming pan thereon and air intake openings around said pan, a liquid fuel feed pipe projecting upwardly through said pan and extending to a point a considerable distance above said base, a retort mounted on said feed pipe and whereto the liquid fuel is delivered, a series of flues depending from the lower portion of said retort and grouped around said feed pipe and adjacent thereto, and having their lower ends near said pan and said air intake open- 125

ings, and a deflecting hood carried by said retort and flaring downwardly therefrom and encircling said flues and feed pipe and cooperating with said base to form a mixing chamber and detector for directing the flames outwardly from said base.

11. A liquid fuel burner comprising a base having a central priming pan and an air intake opening bordering and surround-

ing the pan, a fuel feed pipe, a retort upon the pipe above the pan and flues depending from the retort for delivering vapor or surplus oil upon the priming pan adjacent said air intake opening.

In witness whereof, I have hereunto set my hand this 13th day of December, 1924.

CHARLES M. STROUD.
